Inventor:

John Hollander,
by Joshua R. Hotta
Atty.

UNITED STATES PATENT OFFICE.

JOHN KOLLANDER, OF CHICAGO, ILLINOIS.

CURTAIN-STRETCHER.

No. 877,723.

Specification of Letters Patent.

Patented Jan. 28, 1908.

Application filed October 25, 1907 Serial No. 399,089.

To all whom it may concern:

Be it known that I, JOHN KOLLANDER, a citizen of the United States, residing at Chicago, county of Cook, and State of Illinois, 5 have invented certain new and useful Improvements in Curtain-Stretchers, of which the following is a specification.

My invention relates to curtain stretchers and particularly to that class thereof characterized by a rectangular frame formed of longitudinal and transverse bars adjustably secured together, and each provided with a plurality of pins for attaching the curtains thereto. Usually, with curtain stretchers of 10 this class, it is more or less difficult, in adjusting the members, to get them securely fixed at right angles to each other, although this is important in as much as the proper hanging of the curtains is, to a great degree, dependent thereon.

The object of my invention is to provide a curtain stretcher of the class mentioned, in which the transverse and longitudinal members will be maintained at right angles to each 15 other when the device is set up for use.

A further object is to provide a curtain stretcher which may be readily and quickly adjusted to accommodate any size of curtain.

Other objects will appear hereinafter.

With these objects in view my invention 30 consists generally in a rectangular frame formed of a pair of longitudinal members and a pair of transverse members, each provided with a plurality of pins for attaching the curtains thereto, a two part clamp arranged at each corner of said frame for uniting the longitudinal and transverse members, one part of each said clamp being slidably mounted upon a transverse member and the other 35 upon the longitudinal member and means for maintaining said parts and their respective members at right angles to each other. My invention will be more readily understood 40 by reference to the accompanying drawings 45 forming a part of this specification and in which,

Figure 1 is a plan view of a curtain stretcher embodying my invention, Fig. 2 is a sectional view upon an enlarged scale taken on the 50 line $x-x$ of Fig. 1, and Fig. 3 is a perspective view of the clamp.

Referring to the drawings, 1—1 indicate the longitudinal members and 2—2 the transverse members. These are preferably formed 55 of wood and are each provided with a plurality of pins, 3 for attaching the curtains

thereto. The four corners of the frame formed by the intersection of the longitudinal and transverse members are each provided with a clamp, A. The clamp A is formed of two 60 parts B and C, the former being slidably mounted upon the transverse members, 2 and the latter upon the longitudinal member, 1. The member, B comprises a plate, 5, adapted to rest upon the top of the member, 65 2, a flange, 6, depending into a slot, or groove, 7, formed in the top of said member and a pair of depending arms, 8 terminating at their lower ends in the hooked portion, 9. The member, B, is thus free to slide on the 70 transverse member, 2, but all lateral or torsional movement between the members B and 2 is prevented by the longitudinal rib 2', which fits snugly between the flange, 6 and the depending portions, 8.

The member, C comprises a plate, 10, substantially of the same width as the longitudinal member, 1, and the side flanges 11, which fits snugly against the sides of the member, 1. The member, 1 is freely slidable 80 through the member, C, but is prevented from lateral movement therein by the flanges, 11. Upon the sides of the flanges, 11 are pins or gudgeons, 12. These extend outwardly from said flanges and are adapted to 85 be engaged by the hooks, 9, of the member, B. 13 indicates a clamping screw threaded into the bottom of a recess, 14 formed in the bottom plate, 10, of the member, C. The screw, 13 is provided with a swiveled end, 15, 90 which impinges against the bottom of the member, 1, clamping the members, B and C upon the members, 2 and 1, and binding the latter together. Inasmuch as the flanges, 11, and the flange, 6 are at right angles to 95 each other when the hooks, 9 are in engagement with the gudgeons, 12, it is obvious that the transverse and longitudinal members of the frame will be maintained at right angles to each other when the stretcher is set 100 up for use.

To adjust the stretcher the screw, 13 is loosened after which the members, 1 and 2 may be slid one upon the other until the frame is of the required size, after which the 105 screw, 13 is tightened. To dismember the frame, the screw, 13 is retracted until the swiveled end, 15, rests within the recess, 14, after which the plate, 10, may be raised sufficiently to disengage the gudgeons, 12 from 110 the hooks, 9.

Having described my invention what I

claim as new and desire to secure by Letters Patent, is:

1. In a curtain stretcher a longitudinal member and a transverse member each provided with a plurality of pins in combination with a separable two part clamp connecting said members; one part of said clamp being slidably mounted upon the transverse member and the other upon the longitudinal member and means for clamping them upon their respective members, the parts of said clamp being readily detachable without removing them from their respective members, substantially as described.
2. In a curtain stretcher a transverse member and a longitudinal member, each provided with a plurality of pins, a two-part clamp connecting said members, one part thereof being slidably mounted upon said transverse member and having depending arms, and the other part being slidably mounted on the longitudinal member and co-acting means upon said arms and the last said part for detachably connecting the parts of the clamp, substantially as described.
3. In a curtain stretcher a transverse member and a longitudinal member, each provided with a plurality of pins, a two part clamp connecting said members, one part thereof being slidably mounted upon said transverse member and having depending arms terminating in hooks at their lower ends

and the other part being slidably mounted upon the longitudinal member and having gudgeons adapted to engage said hooks, substantially as described.

4. In a curtain stretcher a longitudinal member and a transverse member each provided with a plurality of pins, in combination with a two part clamp connecting said members, one part thereof being slidably mounted upon said transverse member and comprising a plate portion adapted to rest upon the top of said member and having a depending flange, said member being grooved to receive said flange and a pair of arms depending from said plate and terminating in hooks at their lower ends, the other part of said clamp being slidably mounted upon said longitudinal member and comprising a bottom plate portion having side flanges adapted to fit snugly against the sides of said member and gudgeons on said flanges adapted to be engaged by said hooks and a clamping screw arranged in said bottom plate, substantially as described.

In testimony whereof I have signed my name to this specification in the presence of two subscribing witnesses.

JOHN KOLLANDER.
